UNITED STATES PATENT OFFICE.

ARTHUR EDMUND GORSE, OF WEST BROMWICH, COUNTY OF STAFFORD,
ENGLAND.

INKSTAND.

SPECIFICATION forming part of Letters Patent No. 425,780, dated April 15, 1890.

Application filed February 10, 1890. Serial No. 339,932. (No model.) Patented in England November 1, 1886, No. 14,013; in Germany April 17, 1887, No. 41,309, and in France April 19, 1887, No. 182,961.

To all whom it may concern:

Be it known that I, ARTHUR EDMUND GORSE, machinist, of 71 New Street, West Bromwich, in the county of Stafford, England, a subject 5 of the Queen of Great Britain, have invented a certain new and useful Improved Inkstand, (patents for which have been granted in the following countries: Great Britain, November 1, 1886, No. 14,013; Germany, April 10, 1887, No. 41,309; France, April 19, 1887, No. 182,961,) of which the following is a specification.

An arrangement of the lids or covers of inkstands to work by levers or other mechanical movement, so that one lid or cover only 15 can be uncovered or open at one and the same time, thereby making it impossible to dip the pen in any well except the one in use, and an arrangement of levers to enable all 20 or any of the lids or covers to be uncovered or open together. The elbow or other levers for operating the covers are by preference pivoted to a fixed eye inside the stand-frame, with a finger-piece projecting, by which each 25 cover is operated. The upper end of the elbow-lever then carries a connecting-rod to another elbow-lever hung at the back of the lid, the end being attached to the lid, so that when the finger-piece is pressed down the lid 30 belonging thereto opens. Now each back elbow-lever is attached to a cord or chain running along the back of the stand, by preference under the frame and inside thereof, and sufficient slack only is allowed to permit 35 one lid to open at one time. Should it, however, be absolutely necessary to have two or more open at once, more slack may be given to the cord or chain by a thumb-screw or other equivalent liberation to allow this, 40 and the thumb-screw also allows any stretching or wear to be taken up.

In order that my invention may be clearly understood and more easily carried into practice, I have appended hereunto a sheet of 45 drawings, upon which I have illustrated one example of how the details may be worked out, and from which other designs may be arranged without departing from the principle thereof, for it will be readily understood

that the design and details thereof may be 50 greatly varied.

Figure 1 is a section through the inkstand Z on line A B, showing the ink-pot closed. Fig. 2 is a sectional plan showing the ink-pot lids C and D down and E up and the various 55 levers inside. Fig. 3 is a section on line H J, showing one ink-pot open.

The lids C D E of the ink-pots X are hinged at k^2 to the stand Z. Attached to these lids are the elbow-levers K, through the eyelet 60 end of which, at k' , the cord L is threaded, which also passes through the small eyelets l' , which are fixed to the inside of the stand Z. The cord L is sufficiently slack to allow one of the crank-levers K to be forward, so 65 that the lid may be open, as shown by Fig. 3. These elbow or crank levers K are connected with other elbow or crank levers M, which are mounted at m^2 by the rods N, the arms m' of the cranks projecting through the slot 70 z^2 in the stand, and ornamented at their ends m^3 to form finger-keys, by the depression of which any lid may be opened. This opening action tightens that portion of the cord passing through the levers of the remaining lids 75 and closes them, as shown in Fig. 1. By the adjustable screw P the cord L may be slackened or tightened, so as to keep all lids closed or allow any or all to be opened at the same time or to compensate the stretch. 80

The inkstands admit of being made in almost any external design and material.

What I then claim is—

1. A series of ink-wells having their covers mounted on levers, in combination with an 85 operating-cord for said levers, and an adjusting device for regulating the slack of said cord, in order that one ink-well or more than one, as preferred, may be uncovered by pulling said cord, substantially as set forth. 90

2. A series of ink-wells and their covers, in combination with levers on which said covers are mounted, a cord connecting said levers and arranged for closing one or more of said covers by pulling on said cord, and a series 95 of keys and levers communicating with the levers which support said cover, in order that the operation of any key may turn back the

cover of the inkstand corresponding thereto, the consequent pull on the cord closing the other wells, substantially as set forth.

3. A series of ink-wells, in combination with
5 a casing which supports them and has a cor-
responding series of openings in front, a series
of levers supporting the covers of said wells,
and a second series of levers connected, re-
spectively, to the corresponding cover-sup-
10 porting levers, and provided outside of said

case with keys which are allowed to protrude by said openings, substantially as set forth.

In testimony that I claim the foregoing as my own I affix my name in the presence of two witnesses.

ARTHUR EDMUND GORSE.
